KEYBOARD FOR MUSICAL INSTRUMENTS
AND KEYS THEREFOR

Nelson J. Jewett, Arlington County, Va.; John W. Jackson, executor and trustee of said Nelson J. Jewett, deceased

Application August 23, 1946, Serial No. 692,419

13 Claims. (Cl. 84—433)

1

The invention relates to keyboards and keys therefor, of the type utilized in pipe organs, electronic organs and the like.

In a predecessor of the present pipe organ—the "tracker" organ, the keys served as levers actuating a bell crank which in turn pulled upon a member to mechanically open a pipe valve. For this use, a key of considerable length was necessary to secure the required leverage. It is within the ability of any organist to read music upon and play the piano, the keys of the organ and piano being identical in finger area and arrangement. In the piano, the keys are also levers used to actuate a mechanical "action" to cause the hammers to strike the strings, and length of key is imperative.

In the evolution of the pipe organ when it was desired to cause pressure on the key to actuate a circuit closer, the easiest and most obvious course was to merely place a circuit closer under each key, the key being of the old type.

One result of use of the long keys, now conventional, is that a minimum drop between manuals, of a plural manual organ, is required in order to provide a frame for support of each bank of keys and to allow the long keys of each manual to project below the next higher manual. This drop has become standardized at two and one half inches. It resulted that it is impossible, with conventional keys and as a practical matter to build a console of two or more manuals, with a drop between manuals of substantially less than the standard.

Among the objects of the present invention are: to provide keys of a character to make possible the production of a plural manual organ with as little drop between manuals as desired; to provide a keyboard wherein the support for the keys of a plural manual organ may be made of thin sheet material; to provide a support of the respective keys of a plural manual organ made integrally by sheet metal stamping; to provide a keyboard "chassis" of sheet material which may be prewired and upon which the keys may be assembled in completely operative relation by mere plugging of a terminal or terminals carried by the respective key switches into sockets provided therefor on the said chassis; to provide a form of key and switch that may be produced in quantity of the necessary shapes by a manufacturer of electrical apparatus best equipped for such manufacture; to provide a novel form of double touch apparatus; to simplify the manufacture of organ consoles and to

2

lessen the cost of organ consoles while improving their quality.

Further objects of the invention will appear from the following description when read in connection with the accompanying drawing showing illustrative embodiments of the invention and wherein:

- Figure 1 is a detail plan view of a portion of a keyboard showing keys in place;
 10 Figs. 2 and 3 are transverse sections respectively on lines 2—2 and 3—3 of Figure 1 upon an enlarged scale;
 Fig. 4 is a vertical section on line 4—4 of Figure 1;
 15 Fig. 5 is a view similar to Fig. 4 of a second form of the invention;
 Fig. 6 is a view similar to Fig. 2 of the form of Fig. 5;
 Fig. 7 is a plan view of the form of Figures 1
 20 to 3, inclusive, with the finger tablets removed;
 Fig. 8 is a vertical longitudinal section through a key structure arranged for "second touch";
 Fig. 9 is a detail vertical longitudinal section of a still different form of the invention; and
 25 Fig. 10 is a detail section on line 10—10 of Fig. 9.

As shown, the key support or "chassis" of the keyboard is formed of thin sheet material and comprises horizontal key supporting members 11 and risers 12. The risers and supporting members may obviously be formed separately and be joined at the angles by riveting, welding or gluing. If formed of sheet metal, as at present preferred, one or more of the angles may be formed integrally as by die stamping.

Any preferred form of circuit closer may be utilized. Merely for purpose of illustration a simple form of push button parts is shown, comprising: a depressible spring contact 13 anchored at 14 and insulated from the member 11, and a stationary contact 15 which may be grounded on the support 11 if the latter is metallic.

As shown, and in accordance with the invention, the finger contacted portion of the key, or the key tablet 16 of the "white" keys and 17 of the "black" keys are floatingly supported by or fulcrumed upon the spring which returns the circuit closer to normal open position. To provide such floating of the finger tablets, they are formed with grooves or pockets at the sides or ends as indicated at 18, 19 into which project flanges or clips 20.

The spring pressure exerted by the circuit closer, or by any additional springs (not shown) pressing upwardly on the tablet 17 will hold

the bottoms of the grooves or pockets 18, 19 against the clips or flanges. Downward movement of the tablet under playing finger pressure will be limited to the vertical width of the groove or pocket. Pressure adjacent either end of the tablet or either side thereof will cause tilting of the tablet because the pressed end or side is free to move downwardly and the opposite end or side cannot move upwardly. The result is a movement downwardly of the center of the tablet with closure of the circuit. Pressure upon the center of the tablet will move the same bodily downwardly.

The type of circuit closer at present preferred for use is that known as a "precision" or "micro" switch, with which only a small fraction of an inch of movement is necessary.

In the form of the invention shown in Figs. 5 and 6, for illustration the finger tablets are floatingly supported by the springs 13 and held by clip 21 at the front end of the white keys which clip is shown as secured to the riser 12 by screw 22. The front ends of black keys are shown as held by clips 23 mounted on the member 11 and the rear ends of both are shown as held by clips 20 formed on a strip 24 secured to a riser 12 by screws 25.

To hold the tablets 16 and 17, Figures 5 and 6, in laterally spaced position for clearance, the recesses 18 in their ends are preferably pockets, that is they do not extend clear across the width of the keys. The plates 21 and 24 may be continuous across the width of a plurality of keys and the clips 20 may be each a little less than the width of the pockets.

The self-contained key switch shown for illustration in Figures 1 to 4, 7 and 8 is at present the form preferred for use. This preference does not include the circuit closer there-shown, the preferred form of circuit closer being that stated above, for assembly with the key switch. In this form of self-contained key switch switch boxes are provided for each individual key, each self-contained with circuit closer and finger tablet 16 or 17. Three forms for "white" keys and one form only for "black" keys are required. For this purpose a switch box is provided for each key comprising sides 26, bottom 27 and ends 28 in which the circuit closer is secured.

As shown in Figs. 2, 3, 4, and 7, the flanges 20 are shown on the sides 26 of the boxes including the off-set portions contiguous to the black key boxes. In the form of Fig. 8 the flanges are formed on the end walls of the boxes. It is obvious that inturned flanges may be provided on both the side and the end walls of the boxes if desired, with corresponding grooves or pockets in all edges of the key tablets.

With keys acting upon the slight depression contemplated by the invention, there is a possibility of actuating two at once by finger overlap. To prevent such an action there are shown plates 29 carried by the sides of the switch boxes. In the case of the "white" keys the plates 29 are shown as extending upwardly flush with the upper surfaces of the key tablets and with the black keys, to lines below the top of the tablets.

For circuit connections, one side of each circuit closer may be electrically connected to a projecting terminal 30 carried by and insulated from the switch box to be plugged into a socket 31 carried by and insulated from the riser 12, which sockets may thus be prewired before the switch boxes are assembled upon the support. The remaining side of the circuit closer may be grounded upon the switch box to contact the metallic frame

and support or upon a bus wire laid on the support if non-metallic. It is obvious that two terminals may be provided on each switch box if preferred with corresponding sockets upon the supporting structure.

An illustrative form of structure to provide for "second touch" is shown in Fig. 8. As there shown, a switch box is shown provided with a finger tablet 16 with grooves or pockets 18 in its ends. This switch box is in turn formed with grooves or pockets 18' immediately above its bottom, which bottom is supported on a second spring 13' of greater resistance than the upper spring 13. The spring 13' is shown as insulated from the box bottom which it supports. Clips 20' are shown entering the grooves or pockets 18'. A certain pressure upon the floating tablet 16 will close only the upper circuit closer and added pressure will close both the upper and lower circuit closer, the whole switch box of the first touch circuit closer being floatingly supported. By obvious additions a third touch could readily be provided.

It will be at once obvious that the flanges 20, or clips 20 may be provided at all edges of each key instead of at opposite edges only as shown. Also it is within the purview of the invention to use clips at the longer edges but confined to the corners only. Moreover the flanges or clips may take over the upper surfaces of the keys, in which case stop means would be provided below the keys to limit the distance to which the key may be depressed—if the circuit closer itself does not provide sufficient stopping action.

In the form of the invention shown in Figs. 9 and 10 the clip 20" is shown as overlapping the upper surface of the key tablet 16. A member 32 is shown vertically slidable in ways 33 shown as formed on the end of the switch box. The member 32 is shown as formed with a flange and bead coacting with an appropriately shaped groove in the finger tablet 16 for slight pivotal movement. The remaining end of the switch box and key tablet of this form will substantially duplicate that shown, except that the lower end of the member 32 may be arched between its edges to clear a terminal 30 if desired.

The form of the invention shown in Figs. 9 and 10 has the advantage that greater depression of the key may be had if necessary to operate some form of circuit closer or for a desired "touch"—without undue increase of the thickness of the key tablet.

A further advantage of this form of the invention is that sidewise tilt of the keys under finger pressure will be largely eliminated by the guiding means of the vertical depression.

Coiled springs may be used to floatingly support the key tablets in all forms of the invention instead of or in addition to the spring of the circuit closer, as is obvious.

By "floating support" as used herein and in the claims is meant a support of a key slab at or closely adjacent its center of gravity. The term is chosen as a concise expression because of analogy with a body floating in a liquid which will tilt about its center of buoyancy when pressed downward at any edge. For purpose of use as a musical instrument key there is combined with the floating body means to prevent upward movement of any margin.

Minor changes in the physical embodiments of the invention may be made within the scope of the appended claims without departing from the spirit of the invention.

I claim:

1. In a key for electrically actuated musical instruments of the organ type providing successive closure of a plurality of circuits by successively increased pressure force; a plurality of compressible elements, each of said elements floatingly supported on the next element therebelow by resilient means increasing in spring force from the lower to the upper; the upper of said elements exposed for finger contact; circuit closing means below each of said elements for actuation by the depression of the element thereabove.

2. A plural manual key board of the organ type comprising, in combination, a stepped structure formed with a plurality of substantially level key supporting surfaces; a plurality of keys superimposed on each of said surfaces; each key comprising a switch box formed in plan to the shape of a key; said boxes each limited lengthwise substantially to the width of the surface upon which it is superimposed; a movable, finger-contacting member carried by each box; and a circuit closer in each box to be actuated by finger pressure on its finger contacting member.

3. The combination of claim 2 in which said structure consists of thin sheet material.

4. The structure of claim 2 in which the structure is formed of sheet metal carrying terminal sockets for the respective keys electrically insulated from the structure and in which the boxes each carry a terminal electrically insulated therefrom, said terminals connected to one side of the circuit closer, entering the respective sockets when assembled on the structure and locating and securing the boxes in place against upward and lateral movement.

5. In a key for musical instruments of the organ type including a switch box of C, D or E organ key shape to form a part of the key: said switch box having a bottom, and side and end walls; at least one of said side walls formed with a portion offset toward the opposite side wall to provide a shoulder externally of the box, said shoulder dimensioned to fit about one side and a portion of one end of an adjacent "black" or "sharp" key of a key board, and resulting in a narrowed portion to extend along a side of said "black" or "sharp" key.

6. The structure of claim 5 with a contact terminal electrically insulated from the box and projecting from the end of its narrowed end.

7. In a key for musical instruments of the organ type, a switch box, key shaped in plan view; wall structures at least partially closing said box at its bottom and sides; a relatively thin key slab closing the upper side of said box; clip means each carried by a wall of the box and having an-

5 gular portions respectively overlying opposite marginal portions of said slab to limit upward movement of said portions; resilient means pressing said slab to its upward limit of movement; a circuit closer; and means actuated by depression of said slab to close said circuit closer.

10 8. The key structure of claim 7 with resilient means to hold the circuit closer open said resilient means also acting to press the slab upwards.

15 9. The structure of claim 8 wherein said resilient means acts to floatingly support said slab.

10 10. The structure of claim 7 wherein at least one wall of said box carries a connector terminal connected in circuit with the circuit closer.

15 11. A plural manual keyboard structure comprising a stepped structure formed with relatively horizontal and relatively vertical portions of sheet material; connector sockets carried by certain of said portions; a plurality of self-contained key structures each comprising a circuit closer housing and a circuit closing key slab; said key structures each including a connector terminal in circuit with the circuit closer and adapted for co-action with the respective connector sockets; whereby the keys may be assembled with the step structure by mere plugging in of said connector terminals.

20 12. An organ key board structure of sheet material, comprising: at least one horizontal sheet member providing a key supporting surface; and at least one vertical sheet member projecting from one edge of said horizontal member; the width and length of said horizontal member being both substantially equal to the superficial horizontal dimensions of a bank of organ keys to be supported thereby and the vertical extent of the vertical member being not less than the vertical thickness of said keys.

25 13. The structure of claim 12 when made of sheet metal, the horizontal and vertical members being integral with each other at meeting edges thereof.

30 NELSON J. JEWETT.
